GREASE-GUN FILLER.

1,274,452.

Specification of Letters Patent.

Patented Aug. 6, 1918.

Application filed March 15, 1915. Serial No. 14,564.

To all whom it may concern:

Be it known that I, JOHN J. RICHARDS, Jr., a citizen of the United States, and resident of Brookline, in the county of Norfolk 5 and State of Massachusetts, have invented certain new and useful Improvements in Grease-Gun Fillers, of which the following is a specification.

The present invention relates to an instrument adapted to place a charge of grease in grease guns. The object of the invention is to provide an instrument of this character which can be filled by insertion into a mass of grease and then can be inserted endwise 10 in a grease gun and caused to discharge its charge of grease into the gun, placing the charge in any part of the gun desired. Other objects are to provide the filler with 15 means for discharging the same, which can be operated by the thumb and fingers of one hand; to construct the same in such a way that the piston or other device which is employed to discharge its contents may be readily displaced for the purpose of cleaning; to make the filler with a body and a 20 handle portion of a single piece of sheet metal; and in general to furnish a strong, convenient, easily handled and used article of the character indicated, and one which 25 can be made out of a relatively small amount of inexpensive material with high production economy. In the accompanying drawings forming a part of this application,

Figure 1 is a longitudinal sectional view 30 illustrating what I now consider to be the preferred embodiment of my invention.

Fig. 2 is an elevation of the same.

Fig. 3 is an end view as seen from the lower end of Fig. 2.

Fig. 4 is a cross section on line 4—4 of Fig. 2.

Fig. 5 is a sectional view of a detail of construction of the filler.

Fig. 6 is a plan of a detail of construction.

The same reference characters indicate the same parts in all the figures.

The filler comprises a body portion *a*, a handle portion *b*, and an ejector *c*, having an 50 operating handle *d*. The body is of generally cylindrical form, made as a shell open at one end and at one side and of a diameter adapting it to pass readily into the interior of any standard grease gun when one of the

heads of such a gun is removed from the 55 body thereof.

The ejector *c* is a disk which fits the interior of the shell like body *a* in the manner of a piston and is preferably made as a complete circle of which the radius is 60 equal to the internal radius of the shell *a*. This piston disk *c* is connected to a rod *e* which passes through a guide orifice in the handle *b* and is bent into the form of a ring or eye to make the hand operating portion 65 or handle *d*.

Preferably the body of the filler and its handle *b* are made out of a single piece of sheet metal, the blank from which they are produced being cut with a width sufficient 70 for the purpose and having parallel strips extending from one end near the opposite edges thereof. The blank is made up into the final shape by being rolled into tubular form but not to such an extent that the opposite edges *f* and *g* meet. The width of the blank is somewhat more than the semi-circumference of the tubular body so that such edges *f* and *g* are separated by distances less than the internal diameter of the 80 body.

The extensions *b* and *b'* to form the handle are placed at such points that after the blank has been rolled into its tubular form, these 85 extensions will lie symmetrically on opposite sides of the axis of the body. At any desired point in the process of cutting out the blank each of these extensions is formed with a narrow tongue *h* at its end, a circular aperture *i* at a distance back from its end and a 90 semicircular aperture *k* still farther back from its end.

The straight side of the aperture *k* is toward the end of the extension and perpendicular to the side edges of the extension; and the aperture *i* is midway between 95 this straight edge and the base of the tongue *h*, or approximately so. After the body of the filler has been rolled into tubular form as above indicated the ends of the extensions *b* and *b'* are bent toward each other until they 100 overlap and the tongue on the end of each is passed through the aperture *k* of the other and doubled back against the opposite side of the extension or member through which it is passed, in the manner shown in Figs. 2 and 5. The holes *i* in the two extensions are thereby caused to register with one another 105 and they provide the passage and the bear-

ing adapted to admit the rod *e*. The semi-circular form of the aperture *h* is provided merely to enable the die by which it is punched out to be made sufficiently strong. 5 The only essential as to the form of this aperture is that it be wide enough to admit the tongue *h* of the other handle extension and enable such tongue to be doubled around one edge of the aperture in a manner sufficiently 10 secure to prevent its being accidentally dislodged. Any form of aperture which will secure these effects may be used.

It will be appreciated that the two handle extensions *b* and *b'*, being thus constructed 15 and joined, are securely connected together and constitute a sufficiently rigid handle adapted to be grasped with sufficient firmness to enable the filler to be plunged into a mass of stiff grease and to be manipulated 20 as a scoop so as to become filled with the grease. At the same time these handle members form a support and guide for the piston rod *e*, guiding the movements thereof and preventing the ejector or piston from becoming 25 detached from the body. Moreover the extensions before being bent toward each other are carried far enough outward and apart from each other to provide spaces amply wide on each side of the piston rod 30 to admit a man's finger, whereby two of the fingers of the operator's hand may be inserted in the handle while his thumb is placed in the eye *d* to permit operation of 35 the ejector by the fingers and thumb of one hand.

The edge *l* of the blank between the handle extensions *b* and *b'* is provided with a tongue *m*, which is bent outwardly, as shown in Fig. 1, and may be stiffened by a web *n* 40 formed by pressing out a portion of the metal between the edges of the tongue and crossing the line on which the tongue is bent. This tongue is provided for a stop to limit the penetration of the filler into a grease gun.

45 In the handle extensions *b* and *b'*, adjacent to the points whence they spring from the body of the filler, are formed tongues *o* and *o'* integrally united at one end and pressed inwardly at the other end, the latter end being directed toward the open end of the 50 filler. These tongues provide stops adapted to engage the edges of the ejector disk and limit the withdrawal of the latter.

The corners at the open end of the filler 55 body are cut away or notched at *p* and *q* leaving shoulders about equal in width to the thickness of the disk *c* and separated by a distance which is slightly less than the diameter of the filler but greater than the distance 60 between the edges *f* and *g*. When the ejector disk is brought into the zone of these shoulders it may be slipped past them laterally out of the filler, leaving the entire body of the latter open to permit of its being 65 cleaned. At the lower portion of Fig. 1 I

show the disk *c* by dotted lines in the position last described. The rod *e* and disk *c* may be moved from the last named position to the position indicated by dotted lines at the upper portion of Fig. 1 thus entirely 70 removing said rod and disk from the body portion of the filler.

In using the filler to put a charge of grease in a grease gun, the ejector piston is first withdrawn as far as permitted, and the 75 filler is itself first filled with grease. This may be done by plunging the end of the filler body into a mass of grease and rotating it, to cut out a plug of grease, or in any other way. The filler with its charge is then inserted into the end of a grease gun from which the head has been removed, until arrested by the tongue *m*. Then the charge is ejected from the filler. In so ejecting the 80 charge the operator places his first and second fingers in the openings of the handle *b* at opposite sides of the rod *e* and the thumb of the same hand in the eye *d* of the ejector rod, holding the grease gun in the other hand, and presses on the ejector rod with 85 his thumb. When the plug of grease has been so far ejected as to reach the opposite end of the gun, if long enough to do so, before the plunger reaches its inner limit of movement, the shell of the filler is withdrawn while pressure is maintained on the plunger, and finally the entire filler is withdrawn, leaving the charge of grease in the 90 gun. If one load of the filler is not enough to fill the gun, another and as many more 95 loads may be similarly inserted as may be necessary to fill it.

My filler is enough smaller in external diameter than the interior of the gun for 100 which it is to be used that it permits free escape of the air displaced when it is inserted with its charge into the gun; and while the body of the filler remains in the gun, the 105 ejector piston may be moved to propel the charge beyond the end of the filler, in the form of a plug which does not fill the bore of the gun and therefore permits escape of the displaced air, until such plug reaches the farther end of the gun. In this way it 110 is possible to fill the gun completely with grease without entrapping any considerable quantity of air. When grease guns are filled in the ordinary way it has been found impossible to place the grease in the farther end of the gun because pressure applied to a 115 lump of grease to force it into the gun causes the grease to spread and make contact with the walls of the gun and seal the air pocket in the farther end of the gun. It is impossible to fill the barrel of a grease gun completely by ladling grease into one end with the opposite end and sides closed, at least in any reasonable length of time; and as a result much annoyance has been caused by the 120 fact that in using the grease gun much air 125

is expelled with the grease, and the gun has had to be filled a number of times in order to inject an ordinary charge into the machine to be greased. My invention as will 5 be readily seen enables the first charge of grease in an empty gun to be placed in the far end of the gun, because the grease is so held that the air can readily escape before the charge of grease is expanded into contact with the walls of the gun. Thus the 10 first part of the charge can be caused to fill the extreme inner end of the gun chamber and successive parts of the charge can be built up toward the open end until the gun 15 is entirely filled with solid grease and with practically complete absence of air pockets. In construction the filler is strong, rigid, and convenient to handle, while being of inexpensive material and easy to make up. 20 The shell or body of the material is made from a single piece of sheet metal by die work and a simple rolling operation. There is practically no assembling to do, and the device can therefore be made largely by 25 automatic machinery.

What I claim and desire to secure by Letters Patent is:

1. A grease gun filler comprising a sheet metal body rolled into tubular form and 30 having integral longitudinal extensions at one end on opposite sides of the axis of such form, the ends of said extensions being bent toward one another and joined together and provided with a guideway, a piston fitting 35 the interior of said form, and a piston rod connected to said piston and passing therefrom through such guideway.

2. A grease gun filler comprising a sheet metal body rolled into tubular form and 40 having longitudinal extensions at one end on opposite sides of the axis of such form, the ends of said extensions being bent toward and lapped over one another and secured together, their overlapping ends having 45 registering openings in the axis of the form, a piston rod passing through said openings, and a piston secured to said rod located in and fitting the interior of said tubular form, the said extensions providing finger holds at opposite sides of said rod.

3. A grease gun filler consisting of a cylindrical shell open at one side and end, the edges of such side opening being separated by a distance less than the diameter of said 55 shell, a pusher fitting the interior of the shell and being retained therein by said edges, and a rod connected to said pusher, the shell having a guide through which said rod passes and by which it is retained, and 60 the corners of the shell at the open end thereof being cut away sufficiently to permit displacement of the pusher laterally out of the shell.

4. A grease gun filler comprising a sheet

metal body rolled into tubular form and 65 having longitudinal extensions at one end on opposite sides of the axis of such form, the ends of said extensions being bent toward one another and joined together and provided with a guideway, a piston fitting the 70 interior of said form, and a piston rod connected to said piston and passing therefrom through such guideway and the bent portions of said extensions forming finger holds on each side of said rod.

5. A grease gun filler comprising a sheet metal body curved into the form of the segment of a cylindrical shell including more than a semicylinder, said body having strips 75 extending from separated points at one end thereof and being bent together across the axis of the cylinder and overlapped at their ends, such ends having complementary locking tongues and apertures and also having aligned openings to admit a piston rod, said 80 body having on its end from which said strips extend, and between the strips, an outwardly integral lip, and also having inwardly struck stop tongues near the points where said strips are joined to the body, a 85 piston disk fitting the interior of the body shell, and a rod connected to said disk and passing through the said aligned openings.

6. A grease gun filler comprising a sheet metal body curved into the form of the segment of a cylindrical shell including more than a semicylinder, said body having strips 95 extending from separated points at one end thereof and being bent together across the axis of the cylinder and overlapped at their 100 ends, such ends having complementary locking tongues and apertures and also having aligned openings to admit a piston rod, a piston disk fitting the interior of the body shell, and a rod connected to said disk and passing 105 through the said aligned openings.

7. A grease gun filler comprising a sheet metal body curved into the form of the segment of a cylindrical shell including more than a semicylinder, said body having strips 110 extending from separated points at one end thereof and being bent together across the axis of the cylinder and overlapped at their ends, such ends having complementary locking tongues and apertures and also having 115 aligned openings to admit a piston rod, said body having inwardly struck stop tongues near the points where said strips are joined to the body, a piston disk fitting the interior of the body shell, and a rod connected to 120 said disk and passing through the said aligned openings.

8. A grease gun filler comprising a sheet metal body curved into the form of the segment of a cylindrical shell including more 125 than a semicylinder, said body having strips extending from separated points at one end thereof and being bent together across the

axis of the cylinder and overlapped at their ends, such ends having complementary locking tongues and apertures and also having alined openings to admit a piston rod, said body having on its end from which said strips extend, and between the strips, an out-turned integral lip, a piston disk fitting the interior of the body shell, and a rod con-

nected to said disk and passing through the said alined openings. 10

In testimony whereof I have affixed my signature in presence of two witnesses.
